UNITED STATES PATENT OFFICE.

JOHN BRESMAN, OF SAN FRANCISCO, CALIFORNIA.

SPRING-HEEL FOR BOOTS OR SHOES.

SPECIFICATION forming part of Letters Patent No. 601,549, dated March 29, 1898.

Application filed January 28, 1897. Serial No. 621,089. (No model.)

To all whom it may concern:

Be it known that I, JOHN BRESMAN, a citizen of the United States, residing at San Francisco, in the county of San Francisco and State 5 of California, have invented certain new and useful Improvements in Spring-Heels for Boots or Shoes; and I do hereby declare that the following is a full, clear, and exact description thereof.

10 The present invention relates to a certain new and useful spring-heel for boots or shoes, which consists in the arrangement of parts and details of construction, as will be herein-after fully shown in the drawings and de- 15 scribed and pointed out in the specification.

The object of the invention is to provide a simple and inexpensive spring-heel for use more especially in connection with shoes worn by ladies or light boots or shoes used by gentlemen, in order that a soft, easy, and noise- 20 less heel may be provided for the shoe.

Referring to the drawings forming a part of this application, Figure 1 is a side view, partly broken away, of a shoe with the spring- 25 heel secured thereto, the heel being in section. Fig. 2 is a bottom plan view showing the top or upper layer of the heel partly broken away, and Fig. 3 is a longitudinal sec- 30 tional view taken on line $\alpha\alpha$, Fig. 2.

In the drawings the letter A is used to indicate an ordinary walking-shoe, and A' to indicate the sole thereof. The heel of the shoe is composed of the layer of rubber B, which is cemented or otherwise secured to 35 the sole of the shoe. This rubber layer forms a soft resilient cushion for the heel. To the rubber cushion is cemented or otherwise af- 40 fixed the layer of leather 1, which layer has formed at each side thereof the openings or 45 sockets 2 3, which sockets are connected by the groove 4. Within the sockets 2 3 are fitted the coiled springs 5 6, which are formed by a single piece of wire, being connected by the body portion 7, which lies in the groove 45 or channel 4. These springs are held securely in place by means of the screws α , which pass through the rubber cushion B and the sole A' of the shoe, the head of the screws engaging the lower end of the springs. These screws 50 give additional strength to the heel and prevent the parts from being separated from each other and from the sole of the shoe in case

the cement should give to the strain which the heel is subjected to. After the parts have been properly united the leather layer 1 55 is covered by the leather tap b, which is secured thereto by short nails or screws b'.

The metallic springs 5 6 are employed in order that the spring of the heel may be preserved after the resiliency of the cushion B 60 has been destroyed, and by the use of these springs I am enabled to make use of much heavier rubber than otherwise could be employed for this purpose.

At the front of the heel a U-shaped groove 8 65 is cut through the top of the heel and layer 1, and between the said layer and rubber cushion is interposed a small metallic plate 9, to which is suitably secured the swinging or slide valve d. This valve opens or closes an air- 70 opening d', formed through the plate 9, rubber cushion B, and the sole A'. This air-opening serves as a ventilator, through which air is admitted to the shoe when the valve is thrown to uncover the said opening. The 75 valve being under control of the wearer of the shoe the ventilator may be opened or closed at will. This is an important feature in connection with the patent-leather or enameled shoes. 80

Having thus described my invention, what I claim as new, and desire to secure protection in by Letters Patent, is—

1. In a spring-heel for boots or shoes, the combination with the rubber cushion secured 85 to the shoe, of a series of springs abutting against and fastened to the rubber cushion, and of the tap covering the springs and cushion.

2. In a spring-heel for boots or shoes, the 90 combination with the rubber cushion secured to the shoe, of the leather layer fastened to the rubber cushion and provided with sockets or recesses, the springs located within said sockets or recesses and fastened to the rubber cushion and to the shoe, and of the tap 95 which covers the leather layer and springs.

3. The combination with a boot or shoe, of a spring-heel secured thereto, said heel consisting of a rubber cushion, springs and a tap, 100 of an air passage-way formed through the sole of the shoe and spring-heel, and of a sliding valve for opening and closing the air passage-way.

4. The combination with a boot or shoe, of
a rubber heel-lift secured thereto, a leather
lift next to said rubber lift and provided with
a socket or recess, a spring in said recess
bearing against said rubber lift, and means
5 acting to secure both the spring and the rub-
ber lift to the shoe, substantially as de-
scribed.

5. The combination with a boot or shoe, of
10 a heel-lift secured thereto and provided with
recesses or sockets connected by a channel or
groove, springs in said recesses or sockets, a

connecting portion for said springs lying in
said channel or groove, and means acting to
secure said springs in said recesses or sock-
ets, and to secure the lift to the boot or shoe. 15

In testimony whereof I affix my signature,
in presence of two witnesses, this 5th day of
January, 1897.

JOHN BRESMAN.
